MUZZLE CLOSING MECHANISM

Victor F. Lucht, Washington, D. C.

Application June 2, 1943, Serial No. 489,351

10 Claims. (Cl. 89—31)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to muzzle closing devices for guns of fairly large calibre, for example, 75 mm. and more particularly, for aircraft-carried guns of this calibre range. Such guns because of their size and weight and the force of their recoil, are usually placed in the fuselage of the aircraft and fire forwardly of the plane. Under such conditions the air flow aft of the plane blows through the gun barrel when the breech is opened into the cockpit of the aircraft. Considerable of the toxic gases of the products of the explosion remain in the gun barrel upon the firing of a shell, and are carried with the indraft of air through the breech when it is opened following the gun discharge. The gas entering the cockpit is especially injurious to the crew because of the enclosed nature of the cockpit and the confined space thereof.

The object of this invention is to provide a muzzle closing device which would rectify this condition by closing the muzzle to the air stream except when the gun is fired, at which time the breech is of course closed, so that there will be no air inrush during firing. Allied with this object, a further object is to provide a muzzle closing device which will close the muzzle immediately after its discharge, at which time there will be the maximum residue of toxic gases in the barrel; moreover, the breech is soon after opened for reloading and would permit such gases to be blown into the cockpit were the muzzle allowed to remain open to the air flow.

For the attainment of these and such other objects of invention as may herein appear or be pointed out, I have shown an embodiment of my invention in the accompanying drawings, wherein:

Fig. 1 is a top view of a gun showing the muzzle device in closed condition;

Fig. 2 is a longitudinal section through the gun, with the muzzle device in closed condition;

Fig. 3 is likewise a longitudinal section, but with the muzzle device in open condition;

Fig. 4 is a cross-section taken on the line 4—4 of Fig. 2;

Figs. 5a to 5f are schematic illustrations referred to in the specification as an aid to explain the operation of the device;

Figs. 6 and 7 are detail views of a segmental blade forming part of the muzzle closing assemblage;

2

Fig. 8 is a cross-section on line 8—8 of Fig. 2; Fig. 9 is an enlarged detail of the V-notched finger, and

Figs. 10 and 11 illustrate the mechanically operated electric switch referred to herein.

The muzzle-closer comprises a number, four being shown in the drawings by way of example, of segmentary numbers 10 which come together in the closing condition of the device, as shown in Fig. 1 and Fig. 2, in the fashion of a clamshell bucket. Each of the segmentary members is provided internally with an inclined cam surface to engage the gun barrel, as shown in Figure 3, for a purpose to appear and is pivoted at pin 12 to an annular member 14 which is secured at the muzzle end of a long tubular member 15. To provide for the said pivoting of the segmentary members 10 to the said annular member 14, the segmentary members are provided on their inner surface with an L-shaped lug 11, the distal end of which is apertured for the said pivot pin 12. The tubular member 15 is spaced from the gun barrel 1, see Figs. 2 and 3, a sufficient distance to provide clearance for an internally splined tube 16 which is secured, at or near the midpoint of tubular member 15, to the internal face thereof. The internally disposed serrations, i. e. teeth elements and channels, of the splined tube 16 are clearly seen in Fig. 4. An external splined ring 6 secured 20 to the gun barrel 1 is provided with teeth which are receivable in the grooves of the internally splined tube 16 and the teeth of the latter are receivable in the channels of the external splined ring 6. It should be noted that the internally 25 splined member 16 secured to the inner surface of the annular tubular member 15 is of considerable length—hence herein termed a “tube”—compared to the externally splined member 6 secured to the outer surface of the gun barrel—hence 30 herein termed a “ring.”

Tubular member 15 together with its annular head 14 and the segmentary closing members pivoted thereon, and together with the internally 35 splined tube 16 are longitudinally movable from the muzzle-closing position, shown in Fig. 2, rightwardly to the muzzle-opening position of

Fig. 3, and return in the opposite direction. In this longitudinal adjustment, tubular member 15 moves between gun barrel 1 and an outer tubular member 25 which is secured at its right end, to the breech casing 2 of the gun.

Slidable tubular member 15 is provided at its right end with a pair of diametrically opposite pins 13, see Fig. 2, which protrude through elongated slots 23 provided in the stationary tubular

member 25. A tensile spring 15s, one for each of the two pins, is secured to the pin 13, the other end being anchored to a small bracket 25a on the stationary tubular member 25. As clearly seen in Fig. 1, elongated slot 23 is wider than the thickness of pin 13, so that the tubular member 15, to which the pins 13 are secured, as described, has an extent of angular or rotational adjustment. More particularly, tubular member 15 has two positions of angular adjustment, one, in which the teeth of the splined tube 16, which is secured internally to the tubular member 15, as described, are aligned with the intermediate spaces of the splined ring 6, which is secured externally to the gun barrel 1, as described, as shown in Fig. 4.

The normal position of the tubular member 15, i. e., with the muzzle-closer 10 in closing position, as in Fig. 1, is diagrammatically shown in Fig. 5a. The tubular member 15 is in forward or muzzle-ward position, to the left in the figures, with its pin 13 at the left end of slot 23, as seen in Fig. 5a; it is also in the angular position in which the teeth of the splined ring 6 abut the teeth of the splined tube 16. In this position, teeth 6 act as stops preventing the rearward movement of the tubular member 15, thus maintaining the muzzle-closer 10 in closing position. In this position of the parts, see Fig. 5a, the pin 13 is disposed at the upper, as viewed in Figs. 5a and 1, edge of slot 23, and is maintained in this position by means of a V-notched finger 20 pivotally mounted on the stationary tubular member 25 at 20a. As best shown in Fig. 1, the crotch of the V-notch is positioned at or near the upper edge of slot 23 to maintain pin 13 at that edge. The V-finger 20 has a short arm 21 to which is articulated the left end of a long rod 22, the right end of which is located at the breech end of the gun, to the right in Figs. 1-3 and is slidably guided in a sleeve 23 secured to the stationary tubular member 25. Rod 22 terminates in a knob 22k in close proximity to the breech elevating mechanism designated generally as 30. Between knob 22k and the right end of frame sleeve 23 is a compression spring 22s; which normally urges rod 22 rightwardly, to maintain finger lever 20 turned in a counterclockwise sense, with its V-notch aligned with the upper edge of slot 23, as shown in Fig. 1.

In the normal condition of the parts, as shown in Fig. 5a, the spring 15s is under tension tending to pull the pin 13 associated with the tubular member 15 rightward but is blocked by the abutment of the teeth 16 of the splined tube, likewise associated with the tubular member 15, with the teeth 6 of the splined ring associated with the gun barrel. In this normal position of pin 13 at the left of slot 23, Fig. 5a, the muzzle-closer 10 is maintained in closed position. To bring the muzzle-closer 10 to its open position—preparatory to discharging the gun—knob 22k is caused to be moved to the left, to move rod 22 in that direction, causing finger lever 20 to be turned clockwise and its V-notch to cam pin 13 toward the lower edge of slot 23 as shown in Fig. 5b. The knob 22k is pushed leftwardly by the breech elevating mechanism 30, Fig. 1, more particularly by a movable part thereof, such as the rod 31 shown in Fig. 1. As the breech block is elevated (not shown) the compressed spring 31s associated with mechanism 30 causes rod 31 to move leftwardly.

In this position, Fig. 5b, of tubular member 15, turned angularly by its pin 13, tubular member 15 turns slightly in a clockwise direction, as

shown by arrow a, Fig. 4, or rather by the said operation of finger lever 20, spline teeth 16 are moved out of abutting alignment with the teeth of the spline ring 6 associated with the gun barrel. The teeth 16 no longer being blocked by the barrel teeth 6, the tubular member 15 is moved rightwardly by tensioned spring 15s. This rightward movement of tubular member 15 causes the internal cam surface of the members 16 to ride over the gun barrel end forcing the muzzle device 10 to be moved to open position, Fig. 3. The pin 13 associated with the tubular member 15 therefore moves rightwardly towards the right end of slot 23 to the position at its right end shown in Fig. 5c. The right end of slot 23 is provided with an inclined surface 24, which is effective to move the pin 13 upwardly if the pin were continued to be moved rightwardly. However, at this time, Fig. 5c, upward movement of pin 13, i. e., counterclockwise turning of tubular member 15, arrow b, Fig. 4, is prevented by the teeth 6 of the splined ring associated with the gun barrel. The parts are thus left in the condition shown in Fig. 5c, with the muzzle device 10 in open position.

The gun is now fired, the recoil causing the teeth 6 associated with the gun barrel to move rightwardly as shown in Fig. 5d. The rightward movement of the gun barrel in recoil causes the teeth 6 of the spline ring associated with the gun barrel to be moved rightwardly out of blocking engagement with the teeth 16 of the spline ring associated with the tubular member, as shown in Fig. 5d, with the result that pin 13 moves up the incline, as shown in Fig. 5e, the tubular member 15 turning in a counterclockwise direction, arrow b Fig. 4. This turning of tubular member 15 brings the teeth 16 of the splined tube again in alignment with the teeth 6 of the splined tube, as shown in Fig. 5e. Subsequently upon the counter-recoil movement of the barrel, leftwardly in the figures, the teeth 6 of the splined ring associated with the gun barrel moves the tubular member 15, by moving its associated spline teeth 16, to the left, as shown in 5f, thus moving the muzzle device to closed condition, with the tubular member 15 in its leftward position, Figure 2.

Details of the muzzle-closing device 10 are shown in Fig. 8. The segment pieces 10, pivoted on pins 12 of the annular head 14, as previously explained and shown in Fig. 2, are connected to one another by tensile springs 10s which are effective when the muzzle closing device, i. e., segments 10, is moved, by movement of the said annular ring 14 of the tubular member 15, beyond the muzzle, as in Fig. 2, to draw the segments 10 together to closed condition as shown in the said figure. To avoid the possibility of firing the gun when the muzzle device is in closed position, which might occur upon the breaking of an operative part or because of some other mishap, an electrical switch 40, Figs. 10 and 11, is provided in the electrical circuit associated with the firing mechanism (not shown). Switch 40 has a roller 41 which clears through a hole 28 provided in outer tubular member 25. When the inner tubular member 15 is in its rightward position, Fig. 11, at which time the muzzle device 10 is in open condition, the roller 41 is caused to ride on the member 15, being thus moved upwardly to close the switch 40, i. e., to permit the gun to be discharged, inasmuch as the muzzle device is in open position. When however, the tubular member 15 moves to the left, to the po-

sition shown in Fig. 10, the roller 41 drops off the tubular member and opens the switch 40, thus opening the primer circuit, inasmuch as the muzzle device is now in closed condition.

I claim:

1. In a muzzle closing device for a gun, in combination, a tubular member slidably mounted on the gun barrel and adapted to turn through a limited angle, a member secured internally to the said tubular member and itself internally splined, a ring member stationarily secured to the gun barrel and externally splined, the teeth of the said splined member clearing through the interdental spaces of the said stationary spline ring in one angular position of the tubular slide member and blocked by the teeth of the stationary spline ring in a second angular position of the tubular slide member, a second tubular member stationarily secured to the gun breech and provided with an elongated slot having an inclined cam surface at its breech-end, a pin externally projecting from the first-mentioned tubular slide member and received in the elongated slot of the second-mentioned stationary tubular member, the said slot being sufficiently wide to permit the pin to be turned the said limited angle of tubular slide member turning and sufficiently long to permit the pin to be moved with the tubular slide member a distance somewhat greater than the length of the said splined member of the tubular slide member, muzzle closing means at the muzzle-end of the tubular slide member, a tensile spring secured to the said pin and anchored on the said stationary tubular member tensioned to urge the tubular slide breech-ward to move the said muzzle closing means to open position, a forked lever pivotally mounted at the muzzle-end of the elongated slot with the said pin of the tubular slide member received in its fork whereby the tubular slide member is normally maintained in its second said angular position with its spline teeth blocked against breech-ward movement of the tubular slide member under urgency of the said spring, by the spline teeth of the stationary spline ring, means for turning the said forked lever to turn the tubular slide member to its first said angular position with its spline teeth clearing in the interdental spaces of the stationary spline ring, whereat the said tensile spring moves the tubular slide member breech-ward, the said muzzle closing means being moved to open position and the said pin approaching the said cam surface end of the elongated slot, the spline teeth of the tubular slide member being engaged by the spline teeth of the said stationary spline ring to prevent turning of the tubular slide member, the said spline teeth of the spline ring being moved with the gun barrel on recoil breech-ward beyond the spline teeth of the tubular slide member, the said pin of the tubular slide member riding on the said cam surface of the elongated slot whereby the tubular slide member is turned to the second said angular position with the spline teeth in blocking alignment, the teeth of the said spline ring engaging the teeth of the tubular slide member upon counter-recoil to move the tubular slide member muzzle-ward, to bring the said muzzle closing means to closed position, the said pin of the tubular slide member engaging the said forked lever to maintain the tubular slide member in the second said angular position, with the tubular slide member blocked by the abutment of its spline teeth with the teeth of the spline ring against breech-ward

movement of the tubular slide member and with the muzzle closing means maintained in closed condition.

2. In a muzzle closing device for a gun, in combination, a tubular member slidably mounted on the gun barrel and adapted to turn through a limited angle, the said member being internally splined, a ring member stationarily secured to the gun barrel and externally splined, the teeth of the said tubular slide member clearing through the interdental spaces of the said stationary spline ring in one angular position of the tubular slide member and blocked by the teeth of the stationary spline ring in a second angular position of the tubular slide member, a second tubular member stationarily secured to the gun breech and provided with an elongated slot having an inclined cam surface at its breech-end, a pin externally projecting from the first-mentioned tubular slide member and received in the elongated slot of the second-mentioned stationary tubular member, the said slot being sufficiently wide to permit the pin to be turned the said limited angle of tubular slide member turning and sufficiently long to permit the pin to be moved with the tubular slide member a distance somewhat greater than the length of the said spline teeth of the tubular slide member, muzzle closing means at the muzzle-end of the tubular slide member, a tensile spring secured to the said pin and anchored on the said stationary tubular member tensioned to urge the tubular slide breech-ward to move the said muzzle closing means to open position, a forked lever pivotally mounted at the muzzle-end of the elongated slot with the said pin of the tubular slide member received in its fork whereby the tubular slide member is normally maintained in its second said angular position with its spline teeth blocked against breech-ward movement of the tubular slide member under urgency of the said spring by the spline teeth of the stationary spline ring, means for turning the said forked lever to turn the tubular slide member to its first said angular position with its spline teeth clearing in the interdental spaces of the stationary spline ring, whereat the said tensile spring moves the tubular slide member breech-ward, the said muzzle closing means being moved to open position and the said pin approaching the said cam surface end of the elongated slot, the spline teeth of the tubular slide member being engaged by the spline teeth of the said stationary spline ring to prevent turning of the tubular slide member, the said spline teeth of the spline ring being moved with the gun barrel on recoil breech-ward beyond the spline teeth of the tubular slide member, the said pin of the tubular slide member riding on the said cam surface of the elongated slot whereby the tubular slide member is turned to the second said angular position with the teeth of the spline ring in blocking alignment with the spline teeth of the tubular slide member, the teeth of the said spline ring engaging the teeth of the tubular slide member upon counter-recoil to move the tubular slide member muzzle-ward, to bring the said muzzle closing means to closed position, the said pin of the tubular slide member being received in the said forked lever to maintain the tubular slide member in the second said angular position, with the tubular slide member blocked by the abutment of its spline teeth with the teeth of the spline ring against breech-ward movement of

the tubular slide member and with the muzzle closing means maintained in closed condition.

3. In a muzzle closing device for a gun, in combination, a tubular member slidably mounted on the gun barrel and adapted to turn through a limited angle, a member secured internally to the said tubular member and itself internally splined, a ring member stationarily secured to the gun barrel and externally splined, the teeth of the said splined member clearing through the interdental spaces of the said stationary spline ring in one angular position of the tubular slide member and blocked by the teeth of the stationary spline ring in a second angular position of the tubular slide member, a second tubular member stationarily secured to the gun breech and provided with an elongated slot having an inclined cam surface at its breech-end, a pin externally projecting from the first-mentioned tubular slide member and received in the elongated slot of the second-mentioned stationary tubular member, the said slot being sufficiently wide to permit the pin to be turned the said limited angle of tubular slide member turning and sufficiently long to permit the pin to be moved with the tubular slide member a distance somewhat greater than the length of the said splined member of the tubular slide member, muzzle closing means at the muzzle-end of the tubular slide member, a tensile spring secured to the said pin and anchored on the said stationary tubular member tensioned to urge the tubular slide breech-ward to move the said muzzle closing means to open position, a forked lever pivotally mounted at the muzzle-end of the elongated slot with the said pin of the tubular slide member received in its fork whereby the tubular slide member is normally maintained in its second said angular position with its spline teeth blocked against breech-ward movement of the tubular slide member under urgency of the said spring, by the spline teeth of the stationary spline ring, means for turning the said forked lever to turn the tubular slide member to its first said angular position with its spline teeth clearing in the interdental spaces of the stationary spline ring, whereat the said tensile spring moves the tubular slide member breech-ward, the said muzzle closing means being moved to open position and the said pin approaching the said cam surface end of the elongated slot, the spline teeth of the tubular slide member being engaged by the spline teeth of the said stationary spline ring to prevent turning of the tubular slide member, the said spline teeth of the spline ring being moved with the gun barrel on recoil breech-ward beyond the spline teeth of the tubular slide member, the said pin of the tubular slide member riding on the said cam surface of the elongated slot whereby the tubular slide member is turned to the second said angular position with the spline teeth in blocking alignment, the teeth of the said spline ring engaging the teeth of the tubular slide member upon counter-recoil to move the tubular slide member muzzle-ward, to bring the said muzzle closing means to closed position, the said pin of the tubular slide member engaging the said forked lever to maintain the tubular slide member in the second said angular position, with the tubular slide member blocked by the abutment of its spline teeth with the teeth of the spline ring against breech-ward movement of the tubular slide member and with the muzzle closing means maintained in closed condition, and means operated by the breech block mechanism of the gun for turning the said forked lever.

4. In a muzzle closing device for a gun, in combination, a tubular member slidably mounted on the gun barrel and adapted to turn through a limited angle, the said member being internally splined, a ring member stationarily secured to the gun barrel and externally splined, the teeth of the said tubular slide member clearing through the interdental spaces of the said stationary spline ring in one angular position of the tubular slide member and blocked by the teeth of the stationary spline ring in a second angular position of the tubular slide member, a second tubular member stationarily secured to the gun breech and provided with an elongated slot having an inclined cam surface at its breech-end, a pin externally projecting from the first-mentioned tubular slide member and received in the elongated slot of the second-mentioned stationary tubular member, the said slot being sufficiently wide to permit the pin to be turned the said limited angle of tubular slide member turning and sufficiently long to permit the pin to be moved with the tubular slide member a distance somewhat greater than the length of the said spline teeth of the tubular slide member, muzzle closing means at the muzzle-end of the tubular slide member, a tensile spring secured to the said pin and anchored on the said stationary tubular member tensioned to urge the tubular slide breech-ward to move the said muzzle closing means to open position, a forked lever pivotally mounted at the muzzle-end of the elongated slot with the said pin of the tubular slide member received in its fork whereby the tubular slide member is normally maintained in its second said angular position with its spline teeth blocked against breech-ward movement of the tubular slide member under urgency of the said spring by the spline teeth of the stationary spline ring, means for turning the said forked lever to turn the tubular slide member to its first said angular position with its spline teeth clearing in the interdental spaces of the stationary spline ring, whereat the said tensile spring moves the tubular slide member breech-ward, the said muzzle closing means being moved to open position and the said pin approaching the said cam surface end of the elongated slot, the spline teeth of the tubular slide member being engaged by the spline teeth of the said stationary spline ring to prevent turning of the tubular slide member, the said spline teeth of the spline ring being moved with the gun barrel on recoil breech-ward beyond the spline teeth of the tubular slide member, the said pin of the tubular slide member riding on the said cam surface of the elongated slot whereby the tubular slide member is turned to the second said angular position with the teeth of the spline ring in blocking alignment with the spline teeth of the tubular slide member, the teeth of the said spline ring engaging the teeth of the tubular slide member upon counter-recoil to move the tubular slide member muzzle-ward, to bring the said muzzle closing means to closed position, the said pin of the tubular slide member being received in the said forked lever to maintain the tubular slide member in the second said angular position, with the tubular slide member blocked by the abutment of its spline teeth with the teeth of the spline ring against breech-ward movement of the tubular slide member and with the muzzle closing means maintained in closed condition, and means operated by the breech block mechanism of the gun for turning the said forked lever.

5. In a muzzle closing device for a gun, in combination, a tubular member slidably mounted on

the gun barrel and adapted to turn through a limited angle, the said member being internally splined, a ring member stationarily secured to the gun barrel and externally splined, the teeth of the said tubular slide member clearing through the interdental spaces of the said stationary spline ring in one angular position of the tubular slide member and blocked by the teeth of the stationary spline ring in a second angular position of the tubular slide member, a second tubular member stationarily secured to the gun breech and provided with an elongated slot having an inclined cam surface at its breech-end, a pin externally projecting from the first-mentioned tubular slide member and received in the elongated slot of the second-mentioned stationary tubular member, the said slot being sufficiently wide to permit the pin to be turned the said limited angle of tubular slide member turning and sufficiently long to permit the pin to be moved with the tubular slide member a distance somewhat greater than the length of the said spline teeth of the tubular slide member, muzzle closing means at the muzzle-end of the tubular slide member, a tensile spring secured to the said pin and anchored on the said stationary tubular member tensioned to urge the tubular slide breech-ward to move the said muzzle closing means to open position, means engaging the said pin for normally maintaining the said tubular slide member in its second said angular position with its spline teeth blocked by the spline teeth of the stationary spline ring, means for operating the said pin engaging means to turn the tubular slide member to its first said angular position with its spline teeth clearing in the interdental spaces of the stationary spline ring, whereat the said tensile spring moves the tubular slide member breech-ward, the said muzzle closing means being moved to open position and the said pin approaching the said cam surface end of the elongated slot, the spline teeth of the tubular slide member being engaged by the spline teeth of the said stationary spline ring to prevent turning of the tubular slide member, the said spline teeth of the spline ring being moved with the gun barrel on recoil breech-ward beyond the spline teeth of the tubular slide member, the said pin of the tubular slide member riding on the said cam surface of the elongated slot whereby the tubular slide member is turned to the second said angular position with the teeth of the spline ring in blocking alignment with the spline teeth of the tubular slide member, the teeth of the said spline ring engaging the teeth of the tubular slide member upon counter-recoil to move the tubular slide member muzzle-ward, to bring the said muzzle closing means to closed position, the said pin of the tubular slide member being received in the said pin engaging means to maintain the tubular slide member in the second said angular position, with the tubular slide member blocked by the abutment of its spline teeth with the teeth of the spline ring against breech-ward movement of the tubular slide member and with the muzzle closing means maintained in closed condition.

6. In a muzzle closing device for a gun, in combination, a tubular member slidably mounted on the gun barrel and adapted to turn through a limited angle, the said member being internally splined, a ring member stationarily secured to the gun barrel and externally splined, the teeth of the said tubular slide member clearing through the interdental spaces of the said stationary spline ring in one angular position of the tubular slide

member and blocked by the teeth of the stationary spline ring in a second angular position of the tubular slide member, a second tubular member stationarily secured to the gun breech and provided with an elongated slot having an inclined cam surface at its breech-end, a pin externally projecting from the first-mentioned tubular slide member and received in the elongated slot of the second-mentioned stationary tubular member, the said slot being sufficiently wide to permit the pin to be turned the said limited angle of tubular slide member turning and sufficiently long to permit the pin to be moved with the tubular slide member a distance somewhat greater than the length of the said spline teeth of the tubular slide member, muzzle closing means at the muzzle-end of the tubular slide member, a tensile spring secured to the said pin and anchored on the said stationary tubular member tensioned to urge the tubular slide breech-ward to move the said muzzle closing means to open position, means engaging the said pin for normally maintaining the said tubular slide member in its second said angular position with its spline teeth blocked by the spline teeth of the stationary spline ring, means for operating the said pin engaging means to turn the tubular slide member to its first said angular position with its spline teeth clearing in the interdental spaces of the stationary spline ring, whereat the said tensile spring moves the tubular slide member breech-ward, the said muzzle closing means being moved to open position and the said pin approaching the said cam surface end of the elongated slot, the spline teeth of the tubular slide member being engaged by the spline teeth of the said stationary spline ring to prevent turning of the tubular slide member, the said spline teeth of the spline ring being moved with the gun barrel on recoil breech-ward beyond the spline teeth of the tubular slide member riding on the said cam surface of the elongated slot whereby the tubular slide member is turned to the second said angular position with the teeth of the spline ring in blocking alignment with the spline teeth of the tubular slide member, the teeth of the said spline ring engaging the teeth of the tubular slide member upon counter-recoil to move the tubular slide member muzzle-ward, to bring the said muzzle closing means to closed position, the said pin of the tubular slide member being received in the said pin engaging means to maintain the tubular slide member in the second said angular position, with the tubular slide member blocked by the abutment of its spline teeth with the teeth of the spline ring against breech-ward movement of the tubular slide member and with the muzzle closing means maintained in closed condition, and means operated by the breech block mechanism of the gun for actuating the said pin engaging means.

7. In a muzzle closing device for a gun, a gun barrel, a member reciprocal relative to the barrel, a muzzle closing assembly comprising a plurality of complementary foldable sections pivotally mounted on and adjacent the outer end of said member in position to fold over the gun muzzle in the forward position of said member, barrel engaging portions on said foldable sections adapted to engage the end of and slide along said barrel means included in the assembly so constructed and arranged to bias said sections and the barrel engaging portions toward each other and the gun barrel, and means for reciprocating

said member and said foldable sections as an entirety relative to said barrel whereby upon rearward movement of said member and foldable sections relative to the barrel, the barrel engaging portions will be cammed over the end of and along the barrel to unfold said sections against said biasing means.

8. In a muzzle closing device for a gun having a fixed part, in combination, a gun barrel, a member reciprocable on the barrel, a plurality of complementary spring-biased sections hinged to said member and having barrel engaging portions constructed and arranged to slide over the barrel with said member, said sections being shaped to fold over and close the gun muzzle when the reciprocable member is in its forward position, spring means connecting said member to the fixed part of the gun and urging said member to a rearward position wherein said sections uncover the muzzle, means for locking said member in forward position, and means for unlocking said member and surrendering it to said spring means connecting said member to said fixed part whereby said member is moved to bring the sections to muzzle uncovering position.

9. In a muzzle closing device for a gun whose barrel moves in recoil and counterrecoil, in combination, a gun barrel, a member reciprocably mounted on said barrel, a muzzle closing assembly comprising a plurality of complementary spring biased sections rockably mounted on said member and having barrel engaging portions, said sections being constructed and arranged to fold over and close the barrel muzzle when said member is in its forward normal position, springs normally urging said member rearwardly on the gun barrel to bring said section barrel engaging portions into engagement with the end of the barrel to unfold said sections upon the rearward movement of said reciprocable member, locking means carried by said member, locking means carried by the gun barrel cooperating with said member locking means to lock said member in a forward po-

sition, and means operable to disengage both locking means whereby said member can move said sections to a muzzle uncovering position.

10. In a muzzle closing device for a gun whose barrel moves in recoil and counterrecoil, in combination, a gun barrel, a stationary tubular member around the barrel and spaced therefrom and having an elongated slot having a cam surface therein, a tubular member surrounding the barrel and also spaced therefrom and reciprocable with respect to said stationary member, springs connecting the two members and urging the reciprocable member toward the stationary member, a muzzle closing assembly carried by the reciprocable member and comprising a plurality of complementary spring-biased sections constructed and arranged to fold together when the reciprocable member reaches its forward position to close the muzzle of the gun, a grooved tube secured to the inner wall of the reciprocable member, a splined ring secured to the gun barrel and cooperating with said grooved tube to lock the reciprocable member against longitudinal movement with respect to the gun barrel and stationary member, a pin carried by the grooved tube and extending through the slot in said stationary member, a rockable lever on the stationary member normally engaging the pin to hold the grooved tube in locking relation to the splined ring, and means operable to rock the lever to partially rotate said grooved tube in one direction to bring the grooves therein into registry with the splines on said splined ring whereby said reciprocable member will be moved to the rear relatively to the stationary member and gun barrel by said connecting spring, said pin being constructed and arranged to engage the cam surface in said slot substantially at the end of the rearward movement of the reciprocable member to rotate said tube relative to said splined ring in a reverse direction to move said splines and grooves out of registry.

VICTOR F. LUCHT.
